Inventor

L. G. Hallberg,

UNITED STATES PATENT OFFICE.

LAWRENCE GUSTAV HALLBERG, OF CHICAGO, ILLINOIS.

FIREPROOF FLOORING.

SPECIFICATION forming part of Letters Patent No. 659,966, dated October 16, 1900.

Application filed March 26, 1896. Serial No. 585,026. (No model.)

To all whom it may concern:

Be it known that I, LAWRENCE GUSTAV HALLBERG, a citizen of the United States, residing at Chicago, in the county of Cook and State of Illinois, have invented a certain new and useful Improvement in Fireproof Flooring, which is fully set forth in the following specification, reference being had to the accompanying drawings, in which—

Figure 1 is a plan view of the skeleton of a portion of a flooring constructed according to one method in which my invention may be carried out. Fig. 2 is a plan view of a portion of a flooring constructed according to another method in which my invention may be carried out. Fig. 3 is a vertical sectional view showing the attachment of a beam suspension-rod to a wall. Fig. 4 is an end elevation of a wall-anchor for such an attachment. Fig. 5 is a vertical section on the line 5 5 of Fig. 4. Fig. 6 is a vertical sectional view showing the attachment of a beam suspension-rod to a girder. Fig. 7 is a vertical sectional view showing the attachment of the girder suspension-rod to a column. Fig. 8 is a plan view of such an attachment on the line 8 8 of Fig. 7. Fig. 9 is a plan view of the construction shown in skeleton in Fig. 1 filled in. Fig. 10 is a vertical section on the line 10 10 of Fig. 9. Fig. 11 is a vertical section on the line 11 11 of Fig. 9. Fig. 12 is a vertical sectional view showing the attachment of beam suspension-rod to columns according to the method of construction shown in Fig. 2. Fig. 13 is a plan view of such attachment on the line 13 13 of Fig. 12. Fig. 14 is a vertical cross-section on the line 14 14 of Fig. 12. Fig. 15 is a vertical section on the line 15 15 of Fig. 2.

It is the object of my invention to construct a fireproof tile flooring requiring the use of few or no steel beams, thereby cheapening the construction and rendering possible the application of fireproof flooring to many structures to which the cost has hitherto made it inapplicable. I obtain this result by supporting my floor upon a system of sagged suspension-rod in place of the usual girders or beams, the said suspension-rod being anchored at their ends to the walls of the building, to columns, or to other suitable carrying supports. These suspension-rod are the

fundamental elements in this construction and perform the weight-carrying functions of the ordinary beams or girders. Surrounding these suspension-rod I form a body of concrete or other cementitious material, from which the filling-in material may be more conveniently supported than from the suspension-rod themselves. Moreover, downward pressure upon such concrete bodies produces an outward thrust, which counterbalances and is counterbalanced by the inward tension of the suspension-rod and relieves the carrying-supports from any other than a vertical strain.

I am aware that it has already been proposed to make a compound beam or girder consisting of a concrete body, in the bottom of which, below the neutral line, is disposed a tension strip or rod adapted to give to that part of the beam which is subject to tensile strain that quality in which concrete is defective—namely, resistance to tensile strain. In all of these constructions, so far as I am aware, the tension strip or rod is not anchored to any carrying-support, but is anchored either at the ends or at intermediate points of the concrete beam, which is merely for the purpose of preventing slipping. Not only for this reason is such tension strip or rod not adapted to carry any weight, but, further, such tension-strip being usually horizontally disposed would be mechanically incapable of carrying weight.

My construction is radically different in that the suspension-rod are the fundamental elements in this construction. They are sagged or bent downward out of a straight line, their ends are anchored, as in all suspension structures, to weight-carrying supports, and these suspension-rod actually carry the weight of the flooring. The concrete in which these rods are embedded performs two functions, which are both subsidiary. The first is that of holding apart by its lateral thrust under a weight the supports to which the suspension-rod are secured, so as to counteract the pull of the said suspension-rod upon their supports. The second is to give a surface or body to which the filling-in floor material may be secured.

Although in my construction the concrete bodies and the suspension-rod do not form

compound beams or girders in the sense in which the prior constructions referred to do, nevertheless, for convenience of description, I shall refer to such combinations of the concrete body and the suspension-rod as a "beam" or "girder," as the case may be.

My invention as above outlined I have shown and shall describe as carried out according to two principal alternative forms. 10 In the first of these forms, which I shall designate as the "rectangular" form, the girders are arranged parallel to each other and the walls of the building and the beams are disposed transversely thereto. In the second of 15 these forms, which I shall designate as the "radial" form, the beams radiate out from the supporting-columns to the columns directly and diagonally opposite and to the walls of the building. I shall describe first 20 the rectangular form. (Illustrated principally in Figs. 1 to 11, inclusive.)

Referring to the drawings by letter, A designates the walls of a building; B, the main girders; C, columns supporting the same, 25 and D suspension-rods, shown in Fig. 1 as secured at one end with the girder B, and at the other end by the anchors E to the wall of the building. I form the girder B by securing one or more suspension-rods B' at their opposite ends to the collars C', carried by the column C or anchors B² in the wall, or both, according to the position of the girder and the building. The suspension-rods B' are allowed to take a natural curve downward to 30 toward the center of their span. The depth of this curve can be varied at will. It is of the character mechanically known as the "catenary" curve, adapted to support a uniform load along its length. Each column C is provided with a pair of brackets C². I now fill in about the suspension-rods B' the body B³ of the girder, using a suitable mold, so that the girder is skewback in cross-section, as seen in Fig. 6. In the upper surface of the 35 girder I partially embed the anchor-strip B⁴, preferably a T-bar, which serves for the attachment of the ends of the suspension-rods D, which are hooked over the flanges of the T-bar, as at d, or secured thereto in any other 40 convenient manner. The anchors E, to which the remaining ends of the suspension-rods D may be attached or which serve similarly to anchor the ends of the suspension-rods B' to the walls, are embedded in the said walls, as 45 shown in Fig. 3. Each anchor may preferably consist of a single casting, which comprises two vertical pieces E', each provided with a flange e and connected by the cross-piece E² and the horizontal piece E³. The 50 suspension-rods are hooked over the pin e', which bears against the flanges e. Any other form of anchor may be employed for the same purpose. The concrete body D' of the beam D² may be formed about each suspension-rod 55 or pair of rods D in the same way as the similar bodies are formed about the girder suspension-rods B', and the intervals between

the beams so formed may be filled in in any one of several ways. In the drawings, particularly in Figs. 9, 10, and 11, I have shown 70 such filling to consist of flat-arch tile arched in two directions. Between the adjacent beams D², I have shown three rows of such tile, the center tile F being the key-tile, the flat-arch tile F' being disposed on each side 75 thereof and supported by the skewback beams D². It is obvious that a greater number of such rows of tile may be disposed between the adjacent beams D². The said tile are arched longitudinally, as shown in Fig. 10, as well 80 as transversely, as shown in Fig. 11. It is further obvious that the flat arch in this direction may include any desired number of tile.

I shall now describe the second general 85 method of construction, which I have designated as the "radial" type. According to this system the suspension-rods of the beams are directly supported from columns instead of from girders, which themselves rest upon 90 columns. Each of the columns L is provided with a circular or polygonal bracket L', which gives a skewback bearing for the concrete body M of the beams M', formed upon the suspension-rods M². The ends of the said suspension-rods are hooked about a collar L², carried by the column L, or are in any other suitable way secured to the said column. I do not herein claim this form of support for the 95 said suspension-rods specifically, since the same has been described and claimed in another pending application, Serial No. 581,902. The floor-space is thus divided up into triangular spaces, which said triangular spaces may be still further divided up, if desired. 105 In these spaces so formed I fill in, preferably with flat-arch tile N, arched in two directions, as already described with reference to the tile F and F'.

In Figs. 12, 14, and 15, particularly in Fig. 110 14, I show a flat protecting-tile O secured beneath the beam M' and adapted to protect the same from excessive heat.

Having so described one or more specific methods in which my invention may be carried out, I do not limit my invention to any of the precise structures so shown or described. 115

Broadly stated, my invention consists of a system of sagged suspension-rods anchored at their ends to suitable carrying-supports, 120 these suspension-rods supporting and being embedded in cementitious material, forming a body about each rod or pair of rods, and suitable flooring material, either tile, as shown and described, or other equivalent construction, filling in between the concrete bodies aforesaid.

What I claim, therefore, and desire to secure by Letters Patent, is—

1. In a flooring, the combination with suitable carrying-supports, of sagged suspension-rods having their ends secured to said supports, cementitious material filled in about 130 said suspension-rods to form a concrete girder

carried thereby, and suitable flooring material filling in between the said concrete girders.

2. In a flooring, the combination with suitable carrying-supports, of sagged suspension-⁵ rods having their ends anchored to said supports, cementitious material filled in about said suspension-rods to form a concrete girder carried thereby, said girder being formed skewback in cross-section, and flat-arched ¹⁰ tile keyed to and supported between concrete girders so formed.

3. In a flooring, the combination with suitable carrying-supports, of sagged suspension-¹⁵ rods anchored to said supports, cementitious material filled in about said suspension-rods to form a concrete girder carried thereby, an anchor-strip partially embedded in said concrete girder, suspension-rods secured at one end to said anchor-strip and having their ²⁰ other ends suitably supported, and flooring material held in position by said suspension-rods and concrete girders, substantially as described.

4. In a flooring, the combination with suitable carrying-supports, of sagged suspension-²⁵ rods anchored to said supports to form a concrete girder, an anchor-strip partially embedded in said concrete girder above the said suspension-rods, a series of similar suspension-³⁰ rods D, each having one end looped over the edge of said anchor-strip, and their opposite ends suitably supported, and cementitious material filled in and about said latter-named suspension-rods to form a flooring.

35 5. The suspension-rod anchor comprising the vertical pieces E', strengthening-flanges e, cross-piece E², and the horizontal piece E³, substantially as shown and described.

6. In a flooring, the column L; the skew-back bracket L'; the suspension-rod M² anchored to the column; the concrete body M surrounding the said suspension-rod M² and bearing against the skewback bracket L'; and suitable filling material filling in between the beams so formed. ⁴⁰

7. In a flooring, the stationary suspension-rod anchor comprising the vertical pieces E', having lateral strengthening-flanges e, pin e', cross-piece E², and forwardly-extending horizontal piece E³, in combination with the suspension-rod B', having its end hooked over the said pin e', substantially as described. ⁴⁵

8. In a flooring, the column C, the skew-back bracket C², the suspension-rod B', anchored to the column, the concrete body B³, ⁵⁰ surrounding the said suspension-rods and bearing against the said skewback bracket C², and suitable filling material filling in the space between the beams so formed.

9. In a flooring, the columns C, having ⁵⁵ skewback brackets C² secured thereto, suspension-rods B' anchored to the columns, and the concrete body B³ surrounding the said suspension-rods and bearing against the skewback brackets to form a concrete girder, ⁶⁰ an anchor-strip B⁴ partially embedded in the said concrete girder above the rods B', suspension-rods D, having their ends attached to the said anchor-strips and to other anchors in the wall or adjacent girder, and a suitable ⁶⁵ filling material, filling in the space between the beams so formed. ⁷⁰
